[57] CLAIM

The ornamental design for a combined medical syringe
and vial for administering subcutaneous injections, as
shown and described.

DESCRIPTION

FIG. 1 is a front elevational view of a combined medical
syringe and vial for administering subcutaneous injections,
the rear elevational view being a mirror image;
FIG. 2 is a front elevational view of FIG. 1 in an alter-
nate position, the rear elevational view being a mirror
image;

FIG. 3 is a top plan view of FIG. 1;

FIG. 4 is a bottom plan view of FIG. 1; and

FIG. 5 is a side elevational view of FIG. 1 as seen from
the right of FIG. 1, the left side elevational view being
a mirror image.
